HINGE FOR A PIVOTAL BEDFRAME

Melvin E. Roche, Berea, Ohio

Application December 5, 1957, Serial No. 48,782

Term of patent 14 years

(Cl. D5—2)

FIG. 2

In Fig. 1 of the drawing, a novel hinge for a pivotal bedframe is shown in perspective. An associated bed headboard leg and frame runner are shown in dot-dash lines with the novel hinge for illustrative purposes only.

Fig. 2 shows the hinge of Fig. 1 in perspective in a closed position.

Portions of the drawing are stippled to indicate contrast in surface materials.

I claim:

The ornamental design for a hinge for a pivotal bedframe, as shown and described.
